UNITED STATES PATENT OFFICE.

WILLIAM ALLEN RUSSELL, OF LOS ANGELES, CALIFORNIA.

DESIGN FOR A BADGE.

SPECIFICATION forming part of Design No. 31,296, dated August 1, 1899.

Application filed June 14, 1898. Serial No. 683,442. Term of patent 3½ years.

To all whom it may concern:

Be it known that I, WILLIAM ALLEN RUSSELL, a citizen of the United States, residing at Los Angeles, in the county of Los Angeles and State of California, have invented and produced a new and original Design for a Badge, of which the following is a specification, reference being had to the accompanying drawings, forming part thereof.

Figure 1 is a perspective front view of a badge, showing my new design. Fig. 2 is a rear elevation of the badge. Fig. 3 is a side elevation of the badge. Fig. 4 shows the badge in longitudinal mid-section in the plane of the side arms. Fig. 5 shows the badge in longitudinal section in a plane at right angles to Fig. 4. Fig. 6 shows the badge in cross-section on line 6 6; Figs. 2 and 3.

As shown in the drawings, the leading or material feature of my design consists of a slim body A, formed at one end in a straight cylindrical portion 1 and at the middle in a stepped portion, as at 2 3 4, and a smooth tapered portion, as at 5, extending from the stepped portion to the other end of the body and there terminating in a plane which lies

at right angles to the axis of the body and is socketed, as at 6, a neck and ball 7 8 being arranged at the cylindrical end of the body and side arms 9 at the inner end of said cylindrical portion of the body. At the rear side the body has a transverse piercing, as at 10, the ends of which when the badge is viewed from the rear give the appearance of two spots lying in the plane of the side arms. 30 The front side of the body is socketed, as at 11, near the end of the cylindrical portion of the badge-body. The cylindrical portion 10 terminates in a semiglobular portion 1", and the neck 7 is fastened to the apex of said 35 semiglobular portion in line with the axis of the cylindrical body 1. 40

Having described my invention, what I claim as new, and desire to secure by Letters Patent, is—

The design for a badge substantially as herein shown and described.

WILLIAM ALLEN RUSSELL.
